(57) **CLAIM**

The ornamental design for a four position panel mount receptacle shell for tool-releasable solar power connector, as shown and described.

DESCRIPTION

FIG. 1 is a front view of a four position panel mount receptacle shell for tool-releasable solar power connector.

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a front, top perspective view thereof;

FIG. 8 is a back, bottom perspective view thereof;

FIG. 9 is a front, bottom perspective view thereof;

FIG. 10 is a front, right perspective view thereof; and,

FIG. 11 is a bottom, left perspective view thereof.
